UNITED STATES PATENT OFFICE.

JOHN WYCLIFFE LEIGHTON, OF MARYSVILLE, MICHIGAN.

MEANS FOR MAKING BUSHINGS AND THE LIKE.

Application filed April 19, 1921. Serial No. 462,596.

The principal objects of this invention are, to produce metal bushings or the like in which the texture of the metal is rendered hard and wear resisting and capable of withstanding very heavy service.

A further object is to produce by a single mechanical operation a bearing having its internal and external surfaces concentric, thereby reducing the cost of production to the minimum.

The principal feature of the invention consists in closing a die of radially separable segments around a punch and a rough tubular blank to hold them in true axial alignment, the diameter of the punch being greater than the diameter of the hole through the blank, then forcing the punch into the blank so that the metal is subjected to a radial compressive force applied progressively, said punch maintaining a uniform contact with the bushing and holding the metal under compression as it advances.

In the drawings, Figure 1 is an elevational part sectional view of the tools for making the bushing.

Figure 2 is a plan view of the structure shown in Figure 1.

Figure 3 is a horizontal sectional view through the structure on the line 3—3 of Figure 1.

Figure 4 is a side elevational view.

In my co-pending application, Serial No. 425,287 for method of manufacturing bushings and similar articles, I described a method wherein the blank is subjected to a compressive force applied progressively, the tool holding the metal under compression as it advances and the present application embodies the same process but is directed to means for carrying it into effect.

In the form of the invention herein shown a base 1 is secured to the bed plate 2 of a suitable press and supports a circular anvil 3 centrally arranged. At either side the base 1 is formed with jaws 4 in which the links 5 are carried upon horizontal pivot pins 6. The press used is of the double ram type and secured to the outer ram 7 is a plate 8 to which are secured the side guides 9 forming the transverse slideways 10.

Within the slideways 10 are slidably supported the blocks 11 which are recessed to receive the inner ends of the links 5 and which are pivotally connected by means of the link pins 12.

A pair of blocks 13 are secured to the in-

ward faces of the blocks 11. These blocks are recessed to receive the die sections 14, the blocks 13 being formed with shoulders 15 at the top and bottom to hold the die sections from longitudinal movement and cap screws 16 extend through the blocks 13 to hold the die sections in place. Transverse gibs 17 extend into the blocks 13 and into key-ways 18 in the blocks 11.

The die sections 14 are formed with half cylindrical recesses in their meeting faces which at the lower end are enlarged to the diameter of the bushing to be held. The inner ram 19 carries the punch 20 suspended axially over the anvil and the die sections 14 are adapted to close around the punch in a snug sliding fit thereby ensuring the centralizing of the punch in relation to the bushing.

The die sections and their supporting blocks are provided with radial ducts 21 which connect with ducts 22 in the blocks 11 to convey a suitable lubricant to the die.

In the operation of this device the rams are both drawn upwardly. The movement of the outer ram drawing upwardly swings the links 5 on their pivots and the blocks 11 are caused to slide outward in the slideways 10 thus drawing apart and separating the die sections 14. The dies are thus moved upwardly and outwardly clear of the anvil 3 and of the centre punch and the lubricant flowing inwardly washes away any chips or other foreign matter adhering to the punch or die and co-incidentally cools both punch and dies.

The bushing blank B which is preferably a rough casting is placed on top of the anvil either manually or automatically as may be desired and the downward movement of the outer ram, through the action of the links 5 moves the blocks 11 inwardly closing the die sections 14 concentrically around the punch and the blank. The inner ram then moves the punch 20 downwardly so that its inner end, which is preferably squared, engages the blank, the opening through which is of less diameter than the punch.

As the blank and the centre punch are securely confined between the walls of the die the concentricity of the inner and outer walls is ensured.

The compressive force progressively applied by the downward movement of the punch without a cutting effect compresses the metal to a very great density and drags

upon the metal so as to break down the natural cast crystalline formation to a very considerable depth, distorting and rearranging the structure so as to create in the inner bearing surface the maximum quantity of the amorphous binding material of the metal structure and finally extruding the surplus metal from the bottom end of the die.

10 The punch being formed without decreased diameter beyond its entering edge, after first compressing the metal maintains the compression until the entire body is acted upon, consequently there can be no reactive expansion of the metal back of the compressing edge during the inward progress of the punch which would tend to relieve the pressure and thereby disrupt the rearranged structure. The punch is then 15 withdrawn by the operation of the inner ram, following which the outer ram moves upwardly and the segmental die opens out and releases the finished bushing.

20 The feature of dividing the dies and moving the sections thereof apart to release the finished bushing is the most essential element of this invention because if the bushing is treated cold and expanded into a solid die it will seize and its removal in an economical manner is impossible but when the die is opened up by the separation of the segmental members thereof the bushing is released and falls to the bed from which it is recovered in any suitable manner.

25 30 35 The use of an apparatus such as described enables the formation of a bushing in a more accurate and much simpler and cheaper manner than has hitherto been accomplished. The metal is compressed to a remarkable degree of hardness and uniformity of dimensions is maintained.

40 What I claim as my invention is:—

1. Means for making bushings and the like, comprising, the combination with a

press having a pair of reciprocating rams, 45 of a punch carried by one ram, a plurality of radially separable die sections supported by the other ram, means connected with the bed of the press adapted to direct said die sections inwardly to encircle the punch and the blank said punch being operated following the closing of the dies around the blank, and means engaging the bottom end of the blank.

2. In means for making bushings and the like, the combination with a press having a pair of reciprocating rams, the outer ram having radial transverse guide-ways therein, blocks slidably arranged in said guide-ways, links pivotally connected to said blocks and pivotally connected to fixed pivots on the bed, a die formed in sections secured one to each of said movable blocks, said sections being closed together by the downward movement of the ram and adapted to confine a bushing therebetween and separated by the upward movement of the ram through said link connections, and a punch connected with the inner ram and engaged by said die when in its closed position to 70 guide said punch centrally into the bushing confined thereby.

3. Means for making bushings and the like, comprising, a press having a double ram, the outer ram having a pair of transverse radial guides, die blocks slidably supported in said guides, links pivotally connected to said die blocks, rigid pivot supports for the outer ends of said links secured to the bed of the press, said links being 75 adapted to rest in a horizontal position when the dies are closed together to lock the die blocks solidly against outward pressure, a centre punch connecting with the inner ram, and an anvil closing the bottom end of the die.

JOHN WYCLIFFE LEIGHTON.
